FREDERICK H. BRINKKOTTER, OF CALLAHAN'S RANCH, CALIFORNIA.

Letters Patent No. 88,267, dated March 30, 1869.

MACHINE FOR FITTING FELLOES TO WHEELS.

The Schedule referred to in these Letters Patent and making part of the same.

To all whom it may concern:

Be it known that I, FREDERICK H. BRINKKOTTER, of Callahan's Ranch, county of Siskiyou, State of California, have invented an Improved Device for Fitting Felloes to Wagon-Wheels; and I do hereby declare the following description and accompanying drawings are sufficient to enable any person skilled in the art or science to which it most nearly appertains, to make and use my said invention or improvements without further invention or experiment.

The object of my invention is to provide an improved device for fitting felloes to the spokes of wheels; and

It consists in securing to the hub of the wheel, on each side of the spokes, a circular band or ring, to which the mechanism for fitting the felloes may be attached; and, in an apparatus for forcing the felloes to the proper position, and retaining the spokes where desired, so that the felloe can be marked previous to having the mortise bored, and also to correct any irregularity in the felloe, after it has been mortised and fitted to the spokes.

This apparatus may be placed opposite to any spoke in the wheel, by merely changing its position in the rings or bands around the hub, so that the felloe may be operated upon at any point necessary on its circumference, or rim.

To more fully illustrate and explain my invention, reference is had to the accompanying drawings, forming a part of this specification, of which—

Figure 1 is a sectional view of the wheel having my invention attached.

Figure 2 is a front view.

Figure 3 is a back view.

Similar letters of reference in each of the figures indicate like parts.

A is the hub of a wagon-wheel, having the spokes *aa*.

Around each end of this hub, and on each side of the spokes, I place the rings or bands B B, and secure them together by means of bolts, *b b*, or other known device, which pass between the spokes.

The bands B are provided with holes, *e e e*, in their face, opposite each spoke, into which the apparatus for drawing the felloes down against the shoulder of the spokes is secured by means of a hook.

The clamping-frame is composed of a block, C, having three longitudinal slots, *d d d'*, passing through it.

The top of the frame C is bent at right angles, so as to form a projecting cap, D, through which a screw, E, passes.

The screw E, after passing through the cap, is screwed down through a hole in the circular yoke F, and presses against the block G, the ends of the yoke passing through holes in the ends of the block, where it is confined by nuts.

This entire frame is secured to the bands B B by means of the hook *g*, which is placed in the holes *e e e* opposite any spoke to which it is desired to fit the felloe.

The operation of the device is as follows, taking, for instance, a sixteen (16) spoke wheel:

After the tenons are all bored on the ends of the spokes, I lay on one of the bended felloes. If the felloe is out of circle at the point of any spoke, I attach the clamping-frame opposite the spoke, and draw the felloe down to place against the shoulder on the spoke, by turning down the screw E. If the felloe will not stay to its place on the tenons, I use a clamp, K, which clasps the spokes, and which has the arms *f f* passing through the openings *d d* to the opposite side of the clamping-frame, where they are secured and tightened by means of the spring *h*, which is attached to one of the arms, and spring into a rack, *i*, formed on the end of the other arm. I then mark the felloe at the point opposite the centre of each spoke, 1, 2, 3, 4, 5, 6, 7, 8, 9, and bore at the mark opposite 2, 3, 4, 5, 6, 7, 8. No. 1, I bore one twenty-fourth of an inch toward No. 2, and No. 9, one twenty-fourth of an inch toward No. 8. I then take the other half of the bended felloe, and lay it on and clamp it down, as above described, and mark it in the same manner, taking care to bore the first and last holes one twenty-fourth of an inch toward the centre of the felloe. A space of one twenty-fourth of an inch must be left at each joint of the felloe, so that the wheel will not be felloe-bound when the tie is put on.

With this device, I am enabled to fit felloes with great ease and celerity, and so completely binding the parts together that the wheel will be much more serviceable than when made in the ordinary manner.

Having thus described my invention,

What I claim, and desire to secure by Letters Patent, is—

1. The bands B B, secured together on each end of the hub A, for retaining the clamping-frame, substantially as and for the purpose described.

2. The clamping-frame, consisting of the block C, having the longitudinal openings *d d d'* and cap D, together with the block G, yoke F, and screw E, the whole arranged substantially as above described.

3. The clamp K, with its arms *f f*, spring *h*, and rack *i*, for securing the spokes, substantially as herein described.

In witness whereof, I have hereunto set my hand and seal.

FREDERICK H. BRINKKOTTER. [L. S.]
